(57) **CLAIM**

The ornamental design for a handle, as shown and described.

DESCRIPTION

In a preferred embodiment, the nature of this product is a handle for a plumbing fitting such as a shower water control or a faucet.

FIG. 1 is a left, top, front perspective view of a handle embodying my new design;

FIG. 2 is a top plan view thereof;

FIG. 3 is a front elevational view thereof, the rear elevational view thereof being a mirror image of the front view;

FIG. 4 is a left side elevational view thereof;

FIG. 5 is a right side elevational view thereof; and,

FIG. 6 is a bottom plan view thereof.

The broken line representations of post environment in FIGS. 1, 3, 4 and 5 and of an opening in FIG. 6 are for the purpose of illustration only, and forms no part of the claimed design.
